UNITED STATES PATENT OFFICE.

NICHOLAS J. BLAKE, OF COLUMBUS, OHIO.

DRAFTING APPARATUS.

1,310,596.

Specification of Letters Patent. Patented July 22, 1919.

Application filed May 29, 1918. Serial No. 237,314.

To all whom it may concern:

Be it known that I, NICHOLAS J. BLAKE, a citizen of the United States, residing at Columbus, in the county of Franklin and 5 State of Ohio, have invented certain new and useful Improvements in Drafting Apparatus, of which the following is a specification.

This invention relates to drafting and 10 drawing material, and has for one of its principal objects to provide an improved apparatus capable of being employed in connection with a drafting board in lieu of an ordinary T square or angle for purposes of 15 drawing parallel and other straight lines in the process of constructing a sketch or drawing.

Another object of the invention resides in 20 an improved device of this character capable of being readily applied to a drawing board or other similar surface, and which will be simple and convenient to operate, control and adjust and embodying improved features of construction for effecting the 25 drawing of parallel disposed lines.

A further object is to construct the apparatus or device in such manner as to permit the same to be readily shifted from one 30 position to another over the surface of the board to which it is applied, for the purpose of drawing horizontal or oblique lines, and to provide novel means for locking the 35 ruling member thereof in an adjusted position to permit of the inscribing of exactly parallel lines.

A still further and important object of 40 the invention is to provide a ruling member of the apparatus with co-operative means for determining its extent of movement from position to position over the face of the board or other surface upon which it is mounted, and whereby the apparatus will also be capable of serving in the capacity of a rule or scale.

With these and other objects in view, as 45 will appear as the description proceeds, the invention accordingly consists in the novel features of construction, combination of elements, and arrangement of parts hereinafter 50 more fully described and having the scope

thereof particularly pointed out in the appended claims. In the drawings, wherein has been shown the preferred embodiments of the invention:

Figure 1 is a plan view of a drawing 55 board, illustrating the application of my improved ruling apparatus applied thereto,

Fig. 2 is a transverse sectional view taken along the line 2—2 of Fig. 1, and illustrating the cross sectional formation of the ruling member,

Fig. 3 is an end elevation of the ruling member disclosing the bracket construction thereof,

Fig. 4 is a detailed sectional view of the 65 cable clamp,

Fig. 5 is an enlarged fragmentary sectional view of a slightly modified form of ruling member.

Referring more particularly to the details of the invention, the letter A represents any suitable form of drawing board or other similar surface adapted for the preparation and construction of various forms of drawing, and movable over the surface of this board there is mounted a ruling member 1, which in this instance consists of a longitudinally extending body portion 2 and celluloid ruling edges 3, these latter edges being preferably formed from celluloid on account of the transparent properties of this material. The edges 3 are connected with the body portion by providing the latter with longitudinally extending ribs 4, which ribs are positioned within similarly extending grooves 5 formed in the edges 3. Any suitable adhesive may be employed for firmly sealing the joint existing between the ribs and grooves.

The ends of the ruling member are 90 equipped with rigid brackets 6, which brackets are formed to include securing tongue portions 7 and offset roller carrying extremities 8, these extremities being located outside of the margins of the board A for 95 purpose to be presently set forth.

The lower corners of the board A, in this instance, are equipped with cleats 9 and 10 to which the free extremities of a single cord or cable 11 are adapted to be secured. To 100

this end the cleat 9 is provided with a fixed screw 12 upon which is threaded a thumb nut or its equivalent 13, this nut being adapted to be threaded into wedging engagement with the free end 14 of the cable 11. From this point of attachment the cable extends upwardly, at a position spaced from the adjacent edge of the board A, and is passed about a pulley or other similar guide 15 mounted upon the lower face of the member bracket 6.

From this point the cable extends through a longitudinally extending guide passage 16 formed in the ruling member 1, and passes 15 through the entire length of said member, as is clearly shown in Fig. 1. This passage 16 is preferably formed as a part of one of the grooves 5, by forming said groove slightly larger with regard to its transverse area 20 than the corresponding rib 4. This feature of construction provides the guide passage 16 between the side wall of the rib 4 and the adjacent wall of the groove 5.

After emerging from the passage 16, the 25 cable is passed around a pulley 17 mounted upon the underface of the member bracket 6^a, whence it is directed upwardly, as shown at 18 to pass over a pulley 19, or other equivalent guide, mounted upon a bracket 20 located adjacent to one of the upper corners 30 of the board A. From the pulley 20 the cable extends longitudinally across the board, as indicated at 21 and is trained about another pulley 22 carried by a bracket 23 35 mounted upon the opposite corner of said board. From this latter pulley the cord extends downwardly as at 24, and is passed about a second pulley 25 and carried by the underface of the member bracket 6, whence 40 it is trained through a longitudinally extending guide passage 26 formed in the opposite edge of the member 1 as regards the passage 16. From this passage 26, the cord passes about a pulley 27 carried by the 45 bracket 6^a and extends downwardly as at 28 and has its free ends secured to the cleat 10, which latter is provided with a threaded screw 29 and a thumb nut 30, the latter being employed for securely retaining the free 50 end of the cord portion 28.

From this construction it will be manifest that the ruling member may be moved over the face of the board A, and will be guided in its movements by virtue of the location 55 and arrangement of the cord mechanism described, and it will be noted that the ruling member will be capable of being shifted from horizontal to oblique positions, this shifting being compensated for by the peculiar 60 arrangement of the cord structure. However, in order to lock the ruling member in such manner to enable the same to be capable of exact parallel movement, the invention provides a clamp structure 31, which 65 in this instance consists of a base plate 32

which is secured by means of screws to the face of the board A. This plate is formed with upstanding ears 33 to which is pivotally connected a cam lever 34. When this lever is revolved in a downward direction, the toe 70 portion 35 thereof will be swung into clamping relation with the cord 21 so as to prevent the latter from being shifted longitudinally of the board A. From this it will be noted that the ruling member will be permitted to 75 travel in parallel directions only, and can not be adjusted to other positions until the clamping structure has been released to permit of its swinging movement.

Another important feature of the invention resides in providing the portions of the cord 11 which pass through the passages 16 and 26 with a suitably affixed indicator 36. This indicator in the preferred forms of the invention simply being provided by 85 marking in any suitable manner a portion of the cord 11, this marked portion being clearly discernible through the celluloid or other transparent edges 3. These latter edges are graduated or scaled as shown at 90 37 into either a linear or any other measuring scale, as is clearly shown in Fig. 1. Thus when the ruling member is operated, the indicators 36 will move in unison therewith, and the movement of these indicators 95 may be readily observed by comparing the same with the scales 37, thus rendering it possible to accurately determine the extent of movement of the ruling member without 100 employing the services of dividers or other similar measuring devices.

From the foregoing description taken in connection with the accompanying drawing it will be seen that there is provided a device whereby the objects of the invention have been 105 achieved, and that all of the advantageous features of construction above mentioned are, among others, present. The apparatus may be quickly applied to any form of drawing board, is capable of being easily and efficiently operated and in use combines a T 110 square, angle and measuring implements into a single tool, which is characterized by its simplicity of operation and mode of adjustment. It will be appreciated that various changes may be made in the construction of the device from that above set forth. For instance, as shown in Fig. 5, the ruling member may be provided with a ruling edge 40 of different construction from that previously described. This latter ruling edge consists of a plurality of celluloid members 41 which are suitably joined together, to provide a longitudinally extending cord receiving passage 42, through which the cord 11^a is adapted to pass. This cord carries an indicator arm or arrow 43, which is movable over a graduated surface 44. With this latter form of indicator slight movements of the ruling member may be accurately ob- 115 120 125 130

served, and is particularly adapted for fine work.

I claim:

1. In mechanism of the class described, 5 the combination with a drawing board having a plurality of brackets mounted upon the corner edges thereof, of a ruling member movable over said board, a single cord secured to certain of said brackets and trained over guides carried by the remaining brackets and ruling member, and indicating means coöperative with said cord and ruling member for determining the extent of movement of the latter across said board.
- 15 2. In mechanism of the class described, the combination with a drawing surface, of a ruling member provided with a scale movable over said surface, means whereby parallel motion may be imparted to said member, consisting of a single cord adapted to be secured to the lower corner edges of said surface and to be trained over guide devices carried by said member and also the upper corner edges of said surface, and an 25 indicator carried by said cord and located adjacent to said scale to determine the extent of movement of the ruling member across said surface.
- 30 3. In mechanism of the class described, the combination with a drawing table, of a ruling member having a graduated surface movable over the face of said table, cable means coöperatively located with respect to said table and member to permit of parallel motion on part of the latter, and an indicator formed with said cable and situated for coöperation with said graduated surface.
- 35 4. In mechanism of the class described, the combination with a drawing board, of 40 a ruling member provided with scale graduations movable over the surface of said board, means for permitting parallel motion to be imparted to said member, consisting of a single cable having the free ends 45 thereof secured to parallel corners of said board and the central portions thereof passed through guides formed in said member and around fixed guides positioned adjacent to corners of said board opposite to 50 said first named corners, means for locking said cable against movement, and means carried by said cable and coöperative with

said scale graduations for determining the extent of movement of said member over said board.

55 5. In mechanism of the class described, the combination with a drawing board, of a ruling member having guides formed therein movable over the surface of said board, a cable secured to said board and movable longitudinally in said guides, a locking device coöperative with said cable to prevent longitudinal movement thereof, and means for determining the extent of movement of said member over said board.

60 6. In mechanism of the class described, the combination with a drawing board, of a ruling member provided with longitudinally extending openings movable over the face of said board, means for permitting of parallel motion on part of said member, consisting of a plurality of brackets rigidly carried adjacent to oppositely disposed corners of said board, a plurality of guide devices mounted adjacent to the remaining corners of said board, a single cable having one of its ends secured to one of said rigid brackets, guide brackets mounted upon the ends of said ruling member, whereby said cable is capable of being passed around one 65 of said guide brackets, through one of said longitudinally extending openings formed in said member, through the guides formed upon said board, back to the first ruling member bracket, through the second of the 70 longitudinal openings formed in the ruling member, around the opposite of said member brackets, and thence to have its free end secured to one of said rigid board brackets.

75 7. In a device of the class described, the combination with a ruling member, having scale graduations provided therewith, guides formed with said ruling member, a cable structure disposed to pass through 80 said guides whereby the movements of the member over a drawing board are governed, and indicating means coöperative with the scale graduations of said ruling member and said cable means to denote the extent 85 of movement of said ruling member in a 90 guide operation over said board.

In testimony whereof I affix my signature.
NICHOLAS J. BLAKE.
